Primary Examiner — Daniel J Domino*Assistant Examiner* — Lee D. Starr(74) *Attorney, Agent, or Firm* — Fross, Zelnick, Lehrman & Sissu PC; Charles T. J. Weigell, Esq.(57) **CLAIM**

The ornamental design for a snorkel mask communication tube, as shown and described.

DESCRIPTION

The patent or application file contains at least one drawing/photograph executed in color. Copies of this patent with color drawing(s)/photograph(s) will be provided by the Office upon request and payment of the necessary fee.

FIG. 1 is a bottom perspective view of the snorkel mask communication tube showing my new design;

FIG. 2 is a back top perspective view thereof;

FIG. 3 is a right side perspective view thereof;

FIG. 4 is a bottom view thereof;

FIG. 5 is a front top perspective view thereof; and,

FIG. 6 is a top view thereof.

1 Claim, 6 Drawing Sheets
(6 of 6 Drawing Sheet(s) Filed in Color)
